UNITED STATES PATENT OFFICE.

WILLIAM BARRY, OF OSWEGO, NEW YORK.

MAIL-DISTRIBUTING APPARATUS.

No. 908,377.

Specification of Letters Patent.

Patented Dec. 29, 1908.

Original application filed December 20, 1898, Serial No. 699,859. Divided and this application filed April 26, 1900.
Serial No. 14,461.

To all whom it may concern:

Be it known that I, WILLIAM BARRY, a citizen of the United States, residing at Oswego, county of Oswego, State of New York, have invented certain new and useful Improvements in Mail-Distributing Apparatus, a division of my application Serial No. 699,859, filed December 20, 1898; and I do hereby declare the following to be a full, clear, and exact description of the invention, such as will enable others skilled in the art to which it appertains to make and use the same.

This invention relates to mechanism for distributing mail matter or analogous material or articles, and the objects and nature of the invention will be readily understood and apparent from the following description of the construction set forth as one example out of many within the scope of this invention.

The invention consists in certain novel features in construction and in arrangements of parts and in combinations and in details as more fully and particularly set forth and specified hereinafter.

In the accompanying drawings which merely illustrate one example out of many within the scope of my invention: Figure 1, is a partial vertical longitudinal sectional view of an apparatus for carrying out the object of my invention, one of the controlling levers being shown depressed, the packing springs being shown only in one row of boxes. Fig. 2, is a side elevation of the apparatus of Fig. 1, looking at the opposite side thereof, the parts being shown in the same relative positions as in Fig. 1, but showing different gates opened. Fig. 3, is a top plan view of the apparatus. Fig. 4, is a detail sectional view, somewhat enlarged of the front portion of the machine, showing only the first row of the series of receptacles. Fig. 5, is a vertical sectional view taken in the planes of the line 5—5, Fig. 1. Fig. 6, is a sectional plan view taken on the line 6—6, Fig. 4. Fig. 7, is a vertical detailed sectional view taken on the plane of the line 7—7, Fig. 4, all the levers being shown in their normal positions. Fig. 8, is a detail perspective to more clearly illustrate how the lever slides operate on certain rockshafts.

It is now the practice in post offices in this country to face up and arrange mail before marking the same. The letters thus faced

are then run through mail marking machines or stamped by hand for the purpose of affixing the post mark and canceling the stamps. The marked mail matter is then carried to the distributing case and taken in charge by the sorting and distributing clerks who go over the same piece by piece in front of series of boxes or receptacles, each labeled for a certain city or route, and pitch the letters by hand into their various boxes so that all the letters for a certain route or city will be located in the same receptacle. The letters in each receptacle are removed, tied together and a printed slip placed thereon indicating the particular clerk who distributed the mail in the particular bundles.

My invention contemplates an apparatus which will receive the mixed letters or other pieces of mail matter after they have been faced up, wherein the individual letters can be taken from a common or single receptacle, source, bundle or pile and by rapidly moving mechanism distributed to their proper individual boxes or receptacles.

In the specific construction shown in the drawings for the purpose of describing the broad conceptions and features of my invention, a tier or case of boxes or receptacles is shown. This case of receptacles is shown arranged vertically and supported and carried by a suitable frame work, such as *a*. The receptacles are arranged in horizontal rows forming vertical series, as the receptacles are parallel and arranged one above the other in vertical series, as well as one beside the other in horizontal series. Each box is arranged horizontally and closed, preferably at one end, and open at the other so that the letters in each box can be removed in a bundle when desired, and secured together as usual. The boxes are shown arranged in series, as previously described and a letter way or passage is provided for each of said series, and the series of letter ways or passages open to or communicate with a general or main letter way or passage along which all the letters pass and from which each letter moves to or is directed into the proper box or branch passage, from which the letter is directed into the proper box.

In the drawings, each vertical series of boxes is provided with its own letter passage or way arranged vertically beside the same, and each box has a longitudinal side opening. Thus in the example shown in Fig. 1,

twenty four letter boxes or receptacles are shown with six vertical series of boxes, and six vertical letter passages or ways, each opening into the boxes of the particular series it feeds or supplies with letters. These letter ways are indicated by 1, 2, 3, 4, 5, 6, and the boxes of the first vertical series are indicated by A', B', C', D', as they belong to passage way 1, and the remaining vertical series of boxes are correspondingly indicated by the same series of reference letters with the number indicating the particular letter passageways belonging thereto, thus the second series of boxes are indicated by A¹, B¹, C¹, and D¹, the third by A², B², C², D², and so on. In the specific example shown, the general or main letter way or conveyer is arranged above the boxes and at the top of the case, the floor thereof being sustained by the frame work of the case, and the upper ends of the vertical letter ways open through or terminate at said main way. The letters preferably are delivered transversely onto and move along said main way on their flat faces, and suitable gates, stops or strippers are provided at the box or branch passages to direct each letter thereto or to prevent entrance of the letter thereto and permit its movement to some passage beyond. If desired, the floor of said main way can be formed by the gates 1', 2', 3', 4', 5', and each gate can comprise a transverse rock or crank shaft 8, horizontally mounted in the framework at one side of the upper end of the particular box or branch passage, and carrying a series of fingers extending laterally and forwardly therefrom in a direction opposite to that in which the letters move on the main way. These fingers of each gate are located a distance apart and normally lie about horizontally so that all of said fingers extend in the same direction, and the fingers of the gates rest on the top floor of the case of boxes and between the fingers of the next gate. The letters can easily slide or move over the floor of fingers thus formed which is without obstructions to the passage of the letters when all of the gates are in their normal positions. The upper ends of the box or branch passage are preferably curved about as shown, to tilt the letters so that the letters can easily slide thereto, and assume a vertical position therein when the particular gate is elevated. The letters enter said branch or box passage and drop down therein in a vertical position on edge. The lower ends of said ways 1, 2, 3, 4, 5, 6, are closed by curved deflectors or guides D', at the side openings of the bottom boxes D', D¹, D², D³, D⁴, D⁵, and D⁶, so that letters not entering the boxes above will always be directed into the bottom boxes which in the specific construction shown do not need gates. Also in the specific construction shown the last branch or box passage 6, of the series does not need

a controlling gate but has a stop, stripper or guide 6', to direct all letters which have passed the length of the main way into said passage 6.

The box or branch passages have movable stops, strippers, guides, deflectors or gates for each box, excepting the bottom boxes. These gates are preferably all alike, but are all indicated in the drawings by different reference characters to identify each gate with its particular passage and box, thus each gate is indicated by the number of its passage and the letter of its box, and hence the gates to all the "A" boxes are 1A, 2A, 3A, 4A, 5A, 6A, and hence the remaining box gates are indicated according to the same system. Each box gate as shown, comprises a horizontal shaft 1^a, (or 2^a, 2^b, etc., according to the particular gate) mounted transversely of the case at the lower end of the side opening from the branch letter passage into the box, with fingers extending up therefrom to close said opening and normally rest out of the downward path of the letters in the passage, so that when the gate is rocked said fingers will extend across the way and engage the lower edge of the downwardly moving letter and deflect the letter from the way and into the box through its side opening. However various arrangements of gates and boxes can be employed and the letters can fall free by gravity alone to each box or forcible controlling or conveying means can be employed as hereinafter referred to and which as I am at present advised by experience might be broadly preferred. It will thus be observed that the main way gates direct each letter into a particular branch passage wherein gates determine the particular box that each letter enters.

As will be hereinafter pointed out, suitable means are provided whereby the proper gates are actuated to pass each letter into a particular and predetermined box. In the specific construction shown, each gate shaft of the main way and branch passage gates has an extended end provided with a crank and these cranks are operatively connected with certain operating and controlling means. The same system of reference characters is employed in indicating said crank arms. The main gate way crank arms are 1'', 2'', 3'', 4'', 5'', and the branch passage gates are 1^b, 2^b, 3^b, etc. or according to the particular passage and box. All of these cranks are preferably arranged at the back of the case of boxes as more clearly shown in Fig. 2.

The frame of the apparatus as shown, is extended forwardly from the box case and at the top extends downwardly and forwardly to form the main letter way beyond the said gates of said way. At the lower front end of the main way a letter hopper, support or receptacle is shown provided for the bundle of mixed letters, although I may

105

110

115

120

125

130

not employ such a support, as the letters can be otherwise conveniently located.

Various constructions and devices can be provided for this purpose if it be desired to 5 provide a holder for a bundle of letters, though in the specific form shown in the drawings a support, table or floor 10, is provided on which the letters are piled with their addressed faces upwardly and their 10 inner side edges resting against the lower portion of the floor of said main way. This table is vertically movable and is maintained in an approximately horizontal position, and in the drawings is shown carried by the parallel links 11, 11, at the upper front ends 15 pivotally joined to projections from said table and at their lower rear ends pivotally joined to the frame-work so that as the table moves upwardly it approximately follows the curvature of the floor or guide against 20 which the inner edges of the letters abut. This table is shown yieldingly upheld by any suitable means, such as a weight 12, connected with the table or a link by means of 25 a cord passing over a pulley.

Any suitable mechanism or device is provided to move carry or propel the individual letters along the main letter way so that they can be switched off into the proper branch or 30 box letter passages. In the construction shown the letters can be taken along the main way by a series of endless continuously traveling belts 88. This conveyer extends the length of said main letter way and is 35 composed of a series of parallel separated plies or narrow belts moving between and alternating with the fingers of the gates forming the floor of said way, so that the gates are free to rise and fall between the continuously moving belts to deflect the letters downwardly, and without interfering with the free movement of either the belts or the fingers. The rearwardly moving under portions of 40 these belts pass close over and longitudinally of the main letter way so as to positively carry the letters along without fail by frictional contact therewith or if desired the letter engaging faces of the belts can be so formed as to more forcibly catch and carry 45 along each letter. At the front, the said belts are deflected downwardly along the downwardly inclined front of the main letter way, the belts passing over an idler 88'. At the rear end of the main letter way, the said 50 conveyer belts pass around a driving pulley 88² on a shaft mounted in suitable bearings in the frame of the box case and provided with an end driving pulley 88⁴. The opposite portions of the endless belts pass around 55 the pulley 88', carried by a shaft mounted in any suitable and proper manner at the forward portion of the frame-work.

89 is a conveyer co-operating and parallel with the downwardly inclined front portion 60 of the main conveyer 88, and composed of

one or more endless belts mounted on end pulleys beneath and parallel with the pulleys 88', and 88³. The upper face of the conveyer 89, engages and travels rearwardly with the under inclined portion of the conveyer 88, and said conveyer 89, can be driven by frictional contact with the conveyer 88. The bite between the front ends of the two engaging conveyers is conveniently located at the front portion of the apparatus and preferably just above the pile of letters on the supporting table.

The operator can deliver by hand or suitable mechanism (not shown) can be provided to deliver each letter into the bite between said two conveyers which are properly arranged to grip the letters and carry them rapidly up the inclined portion of the main letter way and deliver the same onto the floor composed of the main way gates, along 85 which the letters are preferably rapidly moved by the conveyer 88. Each letter is deflected downwardly from the main way by any elevated gate, and discharged into a branch passage. The letters can fall in the 90 branch or box passage by gravity if desired and be deflected into any predetermined box by any suitable means.

If desired means can be provided to positively move the letters in the branch passages and hold them while moving in the desired position. For instance, in the specific example shown in the drawings, each branch letter way is provided with a conveyer or force feed mechanism, each consisting of 95 an endless continuously operating conveyer 90, extending longitudinally throughout the passage and formed of several parallel separated narrow belts arranged between and alternating with the fingers of the box gates or 100 deflectors hereinbefore described, so that any gate is free to swing through the conveyer and across the branch letter passage and deflect the letter into its particular box through the side opening thereof. The side of each 105 conveyer next to the open sides of the boxes and their gates presses against the box sides and moves downwardly so as to grip the letter as it enters the upper end of the passage and carry the same forcibly by friction or 110 otherwise by reason of the pressure of the belts against the letter. The boxes and gates can be arranged in any suitable manner so 115 that the letters will be piled or stacked in each box in any desirable position.

I show the upper ends of the belts of each conveyer 90, passing around idler pulleys 90², arranged transversely across the upper end of the branch passage just below the main way gate and if desirable mounted on the 125 shaft of said gate between the gate fingers. The conveyer from thence extends throughout the length of the branch passage and through and below the open end thereof, and at its lower end passes around a driving pul-

ley 90', on a shaft 90°. The series of shafts 90°, beneath the respective branch passages, are shown mounted in and transversely of the bottom of the frame, and are all geared to and driven by a longitudinal shaft 91.

92 is a driving belt extending from a pulley on the rear shaft 90°, upwardly to and driving the pulley 88°, and consequently actuating the main conveyer.

10 The various endless conveyers shown in the example illustrated are preferably all continuously actuated at a comparatively high rate of speed, and driving means from any suitable source can be applied by any desirable means to any one of said shafts to actuate the various belts and other driven mechanisms.

Various arrangements of controlling and actuating mechanisms can be employed to set various gates to deposit each letter, taken from the common source, at a particular point box or receptacle of a series. In the specific example shown in the drawings, a key is provided for each box or receptacle.

25 The bank of keys is composed of a series of keys in number equal to the number of boxes or receptacles and each key is provided with characters or printed matter indicating the particular box to which it corresponds.

30 Thus in following out the system of indicating characters adopted, the twenty four keys corresponding to the twenty four receptacles shown, are, respectively, indicated by the same indicating characters. Thus the 35 keys are indicated by A', B', C', D', A², B², C², D², etc. which also indicate the boxes.

The bank of keys is shown arranged in steps and is preferably located beyond the front end of the machine beneath and projecting 40 outwardly beyond the plane of the common pile of mixed letters so that the operator can sit or stand in front of the machine and look down on the keys and also look down on the top-most letter of said pile and thereby

45 easily and quickly read the address of the top-most letter, and depress the key corresponding to the box in which said letter belongs, and then place the letters in the bite between the front portions of the conveyers, or on the front end of the main letter way. It should be noted that the keys and top-most letter of the pile are within the field of vision or view of the operator so that he can almost simultaneously see the address 50 and proper key. All of the key levers are preferably mounted at their inner or rear ends loosely on a shaft 52, extending transversely of the front of the machine and between and secured to the forwardly projecting side frames thereof. All the levers extend horizontally and forwardly from their fulcrum points in approximately the same plane, with their front ends bent upwardly and carrying the keys which are provided with any suitable indicating characters

as before described. The frame sides are provided with rigid forwardly extending arms 54, arranged above the key levers 53, and connected by a transverse rail 55, also arranged above all of the key levers and 70 limiting their upward movement, and carrying vertical separating and guiding plates 55', between the key levers.

56, is a vertical swinging bail having vertical upwardly extending ends beyond 75 the series of key levers and at their upper portions at 56' pivoted to the arms 54. This bail extends beneath all of the key levers and has the beveled upper edge 57. The bail is usually maintained in its normal up-right position by suitable means, such as springs 58 secured to its extended upper ends. Each key lever has a downward projection 58' above the beveled edge of the bail and each projection has an inclined face 85 terminating in an upwardly facing shoulder 59, leaving ample space between the shoulder and the lower edge of the key lever to receive the bail 56. The arrangement is such, that when a key lever is depressed the beveled projection 58', on the beginning of the downward movement engages the beveled edge of the bail and thereby swings the bail to one side and permits it to swing back over the short shoulder 59, of the projection thereby 90 locking the key lever in its depressed position while the bail limits the downward movement of the key lever. The key is thus held depressed or locked until the instant another key is depressed when the same 100 operation is repeated and the locked key is released at the very beginning of the downward movement of the second lever and allowed to return to its normal position under the impulse of a spring and before the 105 lever being depressed has moved but a slight distance.

The key levers are yieldingly held up to their normal position by suitable springs, such as springs 60, secured to the frame with 110 their upwardly springing free ends engaging the under edges of the key levers. Each key lever is provided with a slide 61, operated thereby. The vertical series of separate slides 61, are shown vertically arranged at 115 the front portion of the machine, each with its lower end pivotally joined to its key lever at a point to one side of the fulcrum thereof. The upper ends of the slides are all preferably longitudinally slotted, as shown more 120 clearly in Fig. 4, and a transverse rod 62, is passed loosely through said slots of all the slides. The rod 62, is at its ends secured to the forward ends of lateral arms 63, extending forwardly from and rigid with a rock 125 shaft 64, at its ends mounted in the frame sides and extending transversely thereof. It should be noted that the elongated slots in the upper ends of the slides 61, permit the downward movement of the rod 62 under the 130

impulse of any one of the slides without thereby causing downward movement of the remaining slides and said rod 62, forms a guide for the slides. Each slide 61, is designed to 5 operate or control mechanisms which will direct the letter, when its key is depressed, to the particular box corresponding to and indicated by said key. Various mechanisms can be provided for this purpose.

10 Each key controls a main letter way gate and also a box passage gate, except that the keys corresponding to the "D" boxes do not operate box gates, and the keys corresponding to boxes A^o, B^o, C^o, D^o, do not 15 actuate a main way gate. The reason for this is apparent, as no gates are required for the boxes of the bottom row, nor for the last branch passage from the main way. It might be also noted that the key D^o, corresponding to box D^o, operates no gates at 20 all. However my invention is not limited in these respects as other arrangements of boxes or letter moving and controlling mechanisms might require other arrangements of 25 gates or even dispense with gates, as my invention is not limited to the employment of such, although I prefer them as at present advised from practical tests.

In the drawings, the specific means, 30 closed for controlling the gates comprises a vertical series of transverse rock shafts C, B, A, 5°, 4°, 3°, 2°, 1°. The rock shafts are mounted at their ends in the sides of the frame, and are preferably all located in a vertical 35 plane parallel with and close to the plane of the vertical slides 61, and yet so that each rock shaft extends transversely of all the slides. At the side of the machine, each rock shaft has a crank arm connected by a suitable 40 wire or other connection with certain of the gate cranks and said connections are shown clearly in Fig. 2, arranged at the back of the box case. I prefer in the arrangement of boxes shown, to connect the box 45 or passage gate cranks together in horizontal series as shown in Fig. 2, so that all the A, B, or C, box gates will open and close together respectively. This can be done without interfering with the proper placing 50 of the letters, as the main way gates prevent the letter entering any branch passage except the particular one opening into the particular box corresponding to the key lever depressed.

55 The crank 1°, of rock shaft 1°, is connected by a wire or the like to crank 1°, of gate 1°. Crank 2°, of the rock shaft 2°, is connected to crank 2°, of gate 2°; crank 3°, of rock shaft 3°, to crank 3°, of gate 3°; crank 4°, of rock 60 shaft 4°, to crank 4°, of gate 4°; and crank 5°, of rock shaft 5°, to crank 5°, of gate 5°. It will thus be observed that these five rock shafts just mentioned control the five main way letter gates. The other three rock 65 shafts are, respectively, connected to con-

trol the gates of the rows of A, B, and C, boxes. Thus the crank A', of the rock shaft A, connects to the series of cranks 1°, 2°, 3°, 4°, 5°, 6°. Thus the rock shaft A, controls the gates of the A boxes and must 70 be actuated by each of the six keys corresponding to said boxes. The crank B', of the rock shaft B, in the same way connects with the six cranks of the gates of the B boxes, viz., 1°, 2°, 3°, 4°, 5°, 6°, and hence each 75 one of the six keys corresponding to said B boxes must actuate the rock shaft B. The crank C', of the rock shaft C, connects with the series of cranks 1°, 2°, 3°, 4°, 5°, 6°, of the gates of the C boxes and the rock 80 shaft C, is actuated by all the keys corresponding to the C boxes.

Various means can be employed to cause the slides of the key levers to operate certain rock shafts without operating the remaining 85 rock shafts. This can be conveniently done by series of differently arranged projections. Thus the rock shafts are formed with flanges or arms 67, rigid therewith and projecting toward the slides 61, and normally about 90 horizontal. The edges of said flanges are all slotted or notched to receive all the respective slides. Each slide has one or more cross pins 68, passed therethrough and arranged on the flange or arm of the rock shaft 95 which it is to operate. Hence when the slide is forced down it slides through the flanges or arms which it does not operate but the pin or pins 68 thereof depress the flange or flanges which it should operate and hence 100 rocks the shaft or shafts thereof and opens the proper gates, through the medium of the cranks and pull connections hereinbefore described.

All of the slides connected with the keys 105 representing the boxes, excepting the keys representing the boxes of the bottom and end rows, have two pins to operate two rock shafts and hence open the proper main way gate and branch passage gate. Hence one 110 of said slides has one pin to depress one of the upper five flanges or arms 67, which actuate main way gates, and also a pin to operate one of the lower three flanges to actuate the proper box gate. The slides connected with keys corresponding to the bottom boxes (excepting box D^o) have only one 115 pin 68, each to operate on one of the upper five flanges which control main way gates. The slide connected with the key corresponding to box D^o, has no pins, as no gates are actuated thereby. The slides connected with the keys corresponding to boxes A^o, B^o, C^o, have only one pin 68, each operating on the three lower flanges, respectively, which actuate the box gates. 120

Spring devices 33, are usually employed to return the box gates to their normal positions, and to hold the same yieldingly closed, as shown in Fig. 2. As the main way gates 130

swing upwardly in opening, gravity is usually sufficient to close them, although closing devices can be employed if desirable. In the specific example shown in the drawings, the 5 letters pass down the branch letter ways in an upright position with their long edges usually arranged horizontally. The lower long edge of a downwardly moving letter engages any box gate which is swung open and 10 the letter is hence guided and deflected into the box in its position on edge. The force and pressure applied to the letters by the branch passage belts is sufficient to stack the letters in the boxes in the upright position. 15 Suitable means can be provided to hold the letters together and in the upright position in the boxes. For instance, I show light expansive coiled volute springs 70, in the boxes with the followers carried by the 20 free ends of the springs pressed lightly toward the open sides of the boxes. As the number of pieces of mail matter increases in any box, these very light springs are compressed, and the letters are forced into the boxes by the 25 branch passage conveyer belts. However, as hereinbefore stated, my invention is not limited in this regard as the parts can be arranged to deposit the letters in the boxes in any suitable position or manner. In the 30 specific example shown in the drawings, the inner long edges of the letters piled on the supporting table rest against the downward continuation 7, of the main way from the main way conveyers, and it is only necessary 35 to move the top-most letter of the pile a short distance up said portion 7, of the main way to enable the main way conveyers to grip the letter and carry the same along the main way. The top-most letter of the pile 40 can be rapidly and easily pushed up said portion 7, the short distance necessary before the letter enters the conveyers, by hand or otherwise. The operator usually notes the address of the top-most letter of the pile and 45 presses the key corresponding to the box in which the letter should be deposited, and then causes the letter to be taken up by the main letter way conveyer. The previously 50 set gates deflect the letter from the main way into the particular branch passage, and deflect the letter from the branch passage into the particular box.

It should be noted that the term "letters" employed herein refers generally to mail matter of any sort, kind or condition which any apparatus, within the spirit and scope of my invention, is adapted to receive and handle. It should also be noted that various mechanisms can be added to the apparatus 55 illustrated, or can be taken from the apparatus illustrated without departing from the spirit and scope of my invention.

The invention is not limited to a case or series of boxes, as the letters can be delivered to various predetermined points or locations,

whether such various locations be in the form of compartments, receptacles, boxes, repositories or holders for the letters or otherwise.

The main way gates break joints with each other or overlap in the specific example illustrated, and the fingers preferably taper or are formed of thin material so as not to project far above the top walls of the case of boxes on which said fingers rest. Hence if 75 the belts should press very thin letters down between the fingers the letters would engage and rub along on said top face of the box case without engaging interrupting obstructions. If desired the walls at the rear side 80 of the upper end of each branch passage can have slots therein which the rear ends of the fingers can enter when a gate is elevated.

It is obvious that various changes might be made in the forms, constructions and arrangements of the parts described without departing from the spirit and scope of my invention, although for the sake of making clear the broad features of invention involved in this case, I have described details 90 of construction in the example shown with great exactness, but I do not wish to limit myself to such examples as shown but consider myself broadly entitled to all structures falling within the spirit and scope of 95 my invention.

Having thus fully described my invention what I claim as new and desire to secure by Letters Patent of the United States is;—

1. A mail distributing apparatus comprising a series of receptacles having passages thereto, continuously moving friction letter conveying means for carrying the letters successively from a common source and delivering them separately to predetermined receptacles, letter directing devices, and series of controlling mechanisms corresponding to and indicating the various receptacles and controlling said devices to pass each letter to a receptacle indicated by the particular controlling mechanism actuated.

2. A mail distributing apparatus comprising a holder for the common pile of mixed letters, continuously moving letter conveying means, distributing mechanism, and manually operated controlling means for said mechanism, substantially as described.

3. In an apparatus for distributing individual pieces of mail matter from a common source into predetermined boxes or receptacles of a case or series, a letter support at said common source, continuously moving friction conveying belts, letter directing mechanisms, and series of manually operated controlling means corresponding to the respective boxes and determining the box to which each letter is directed, substantially as described.

4. In combination, in a mail distributing machine, a case or series of boxes or recep-

tacles for mail matter, series of openings to said boxes, continuously moving friction conveyer belts for feeding letters into any one of said openings, and controlling mechanism to cause discharge of each letter into any predetermined opening.

5. In combination, in a mail distributing machine, a case or series of boxes having letter receiving openings therewith, in combination with a continuously moving main letter way conveyer arranged to discharge letters thereto, substantially as described.

6. In an apparatus of the character described, a case or series of boxes or receptacles, each box having a side ingress opening for a piece of mail matter and an open end for egress of the pile of mail matter in the box and continuously moving conveying means for directing pieces of mail matter through said side openings into the boxes, substantially as described.

7. A mail distributing apparatus comprising continuously moving letter conveying means constructed and arranged to take the individual pieces of mail matter from a common source and distribute them to various predetermined points, letter directing mechanisms, and controlling means acting on said mechanisms to determine the particular point to which each piece of mail matter is delivered, substantially as described.

8. An apparatus for receiving letters from a common source and individually delivering them at various predetermined points comprising letter ways, friction belt letter conveyers, independent letter directing gates, and independent controlling devices for operating the gates to determine the delivery point of each letter.

9. In a mail distributing machine, in combination, continuously moving conveyers, letter conveyers, directing mechanisms, said conveyer mechanisms constructed and arranged to successively take individual pieces of mail matter from a common source, and distribute the same to various points or locations, and a series of key levers, indicating the various points of distribution, and acting on said directing mechanisms and predetermined the destination of each piece of mail matter, substantially as described.

10. In combination, in a mail distributing apparatus, continuously moving friction letter conveyers arranged to receive the letters successively from a common source and deliver the same at various locations, series of letter directing means, and series of controlling devices for said means, whereby said means are controlled to deliver the letters at various predetermined locations, substantially as described.

11. In combination, in a mail distributing apparatus, series of separate letter depositories, a continuously moving letter conveyer belt receiving the letters successively

from a common source and delivering the same successively at various points, and series of independent controlling devices, whereby each letter is separately delivered to a predetermined depository, substantially as described.

12. In a mail distributor, the combination of series of letter boxes having letter openings, an endless belt friction letter conveyer common to all of said openings and arranged to discharge letters into any one of them, and sorting and controlling means sorting and determining the particular opening into which each letter shall be discharged.

13. In a mail distributor, the combination of means for individually distributing the pieces of mail matter, a case of letter boxes having letter passages thereto, and a continuously moving letter conveyer common to all the passages and receiving the letters successively from a common source, and controlling means, substantially as described.

14. In a mail distributor, the combination of series of letter boxes, continuously operating letter conveyers arranged to receive the letters from a common source and deliver the same to said boxes, and controlling devices whereby each letter is delivered to a predetermined box.

15. A series of letter receiving receptacles, letter passages communicating therewith, gates at the receiving ends of said passage, and a continuously moving friction belt letter conveyer common to all said passages and so formed that any gate can move through the path of movement thereof and deflect the letter therefrom into the particular passage, substantially as described.

16. In an apparatus of the character described, a series of boxes, a letter passage beside the same and opening into all the boxes, fingered gates for the boxes arranged in the passages, and endless continuously moving letter moving belts arranged longitudinally of the passages and alternating with the fingers of the gates, substantially as described.

17. In combination, series of boxes having a passage communicating therewith, and endless continuously moving letter forcing belts longitudinally of the passage, substantially as described.

18. In a mail distributor, the combination of series of boxes having passages thereto, an endless letter conveyer above the boxes to move the letters, and means to deposit each letter therefrom into a particular passage, substantially as described.

19. In combination, in a mail distributor, a row of letter boxes having ingress openings, an endless letter conveyer moving past said openings, and controlling means provided with manually operating actuating devices, whereby the particular box into

- which each letter is delivered is predetermined, substantially as described.
20. In combination, in a mail distributing apparatus, mechanism for moving the letters from a common source and delivering the same to various predetermined points comprising a series of parallel separated continuously moving belts, series of gates having fingers alternating with the belts and arranged to move out between them to intercept a letter and deflect the same laterally therefrom, and controlling mechanisms, substantially as described.
21. In combination, in a mail distributing apparatus, series of letter boxes having letter receiving openings, a main letter way, an endless continuously moving conveyer over said way, a short endless moving conveyer co-operating with said first mentioned conveyer, and mechanism determining the particular box to which each letter is to be delivered, said letters being all received at a common point by said two belts, substantially as described.
22. In combination, in a mail distributing apparatus, series of letter boxes, a main letter way above the same and extended at one end thereof, a letter support at said end, an endless continuously moving conveyer at said end, an endless continuously moving conveyer extending through the length of said way and along said first mentioned conveyer, and letter directing gates having controlling means, substantially as described.
23. In combination, in a mail distributing apparatus, series of letter boxes arranged in rows with letter passages beside the rows, respectively, continuously moving letter conveying means arranged longitudinally in each passage, gates arranged to intercept the letters therein and deflect the same into any box, means to deliver the letters to any passage, and controlling mechanisms predetermined the particular box into which any letter is to be delivered, substantially as described.
24. In combination, in a mail distributing apparatus, series of letter boxes, continuously moving letter conveying devices, letter directing gates, series of manually operated actuating mechanisms corresponding to and indicating the boxes, respectively, and operatively connected with and controlling said gates, substantially as described.
25. In combination, in a mail distributing apparatus, series of letter boxes, series of continuously moving letter conveyers, and series of letter controlling mechanisms, substantially as described.
26. In a mail distributing apparatus, in combination, series of letter boxes arranged in rows with intervening letter passages opening into the boxes, pulleys at the ends of the passages, endless belts arranged longitudinally of said passages and engaging said pulleys, means for driving said belts, letter directing means, and means for delivering letters into said passages.
27. A mail distributing apparatus comprising letter boxes having letter receiving openings, a continuously moving letter conveyer common to all of said boxes, and separate manually operated controlling means whereby a letter from said mover can be delivered to any box, substantially as described.
28. A mail distributing apparatus comprising letter boxes, a friction belt letter conveyer movable above said boxes, means determining the particular box to which a letter from said conveyer is delivered, and manually operated controlling devices for and corresponding to said means, substantially as described.
29. A mail distributing apparatus comprising a row of letter receptacles having letter receiving openings, a continuously moving letter conveyer arranged to deliver letters to any of said openings, and means independent of the passage of the letters controlling the delivery points of the letters, substantially as described.
30. A mail distributing apparatus comprising a series of letter receptacles, a continuously moving endless friction letter conveyer, means controlling the delivery of letters from said conveyer to any one of said receptacles, and manually operated controllers controlling said means, substantially as described.
31. A series of letter boxes having a passage communicating therewith, a continuously moving letter forcing belt arranged longitudinally of the passage, and means co-operating with the belt and determining the particular box to which each letter shall be delivered, substantially as described.
32. In combination, a plurality of letter receptacles, a continuously moving friction belt letter conveyer arranged above the same, means causing delivery of each letter from said mover to any one of said receptacles, and manually operated movable elements controlling said means, substantially as described.
33. In an apparatus for distributing mail matter, the combination of several series of letter receptacles, series of continuously moving letter conveying devices, arranged to convey the individual pieces of mail matter from a common source and distribute the same to predetermined receptacles, series of means determining the delivery point of each letter, and controlling devices for said means, substantially as described.
34. An apparatus for distributing mail matter, wherein the individual pieces are received from a common source and delivered at various predetermined points of delivery, comprising continuously moving letter conveying means, movable devices controlling

the delivery point of the individual pieces, and controlling means for said movable devices constructed and arranged to return each movable device to its normal position on the 5 operative stroke of a controlling device, substantially as described.

35. An apparatus for distributing mail matter comprising series of receptacles, manually controlled mail matter directing means, 10 and continuously moving letter conveying belts individually receiving the pieces of mail matter from a common source and distributing the same to predetermined receptacles, substantially as described.

15 36. In an apparatus for distributing mail matter the combination of series of receptacles, continuously moving belts for conveying individual pieces of matter, and devices operated independently of the movement of 20 the matter for individually directing the pieces of mail matter and insuring the delivery thereof to predetermined receptacles, substantially as described.

25 37. In an apparatus for distributing mail matter, mechanisms to receive the pieces of mail matter at a common source and distribute the same individually to various predetermined points of delivery, comprising

continuously moving friction letter conveying belts, substantially as described. 30

38. A mail distributing machine having continuously moving letter conveying means for successively receiving the individual pieces of mail matter and separately moving the same to any letter passage and to any 35 letter receptacle along such passage.

39. A mail distributing machine comprising a main letter way and branch letter passages provided with continuously moving friction belt conveyer means for moving the 40 letters along the main letter way and in the branch letter passages.

40. A mail distributing apparatus comprising letter conveying and manually controlled mechanisms for distributing individual pieces of mail matter from a common source to various predetermined boxes or receptacles of a series, said mechanisms comprising a continuously moving endless letter conveyer. 45 50

In testimony whereof I affix my signature, in presence of two witnesses.

WILLIAM BARRY.
